HARRY T. KRAKAU, OF CLEVELAND, OHIO, AND LENDELL A. CONNER, JR., OF PITTSBURG, PENNSYLVANIA, ASSIGNORS TO THE NATIONAL MALLEABLE CASTINGS COMPANY, OF CLEVELAND, OHIO, A CORPORATION OF OHIO.

FRictional DRAFT-RIGGING.

No. 815,023.

Specification of Letters Patent.

Patented March 13, 1906.

Application filed May 3, 1902. Serial No. 105,714.

To all whom it may concern:

Be it known that we, HARRY T. KRAKAU, of Cleveland, Cuyahoga county, Ohio, and LENDELL A. CONNER, Jr., of Pittsburg, Allegheny county, Pennsylvania, have invented a new and useful Frictional Draft-Rigging; of which the following is a full, clear, and exact description, reference being had to the accompanying drawings, forming part of this specification, in which—

Figure 1 is a plan view of our draft-rigging, partly in longitudinal section. Figs. 2 and 3 are vertical sections on the lines II II and III III, respectively. Figs. 4 and 5 are perspective views of the wedges. Fig. 6 is a vertical longitudinal section on the line VI VI of Fig. 1. Fig. 7 is a longitudinal section of the spindle or movable releasing-stop 18. Figs. 8 and 9 are front and rear perspective views of the lever 15. Fig. 10 is a horizontal section of the wedges, showing a modified construction of the releasing device.

In the construction of frictional draft-gear for railway-cars the important ends to be secured are simplicity of construction, which enables the draft-rigging to be applied without complication and expense, durability sufficient to withstand the heavy shocks and blows to which it is subjected when in use, and ease of operation sufficient to allow the frictional action to take place without such preliminary locking action as would prevent the frictional operation. Our invention secures these objects and possesses also other advantages—namely, it affords a construction which is light, and provides means for effecting the release of the frictional parts at or near the end of their motion.

Our invention in its simple form comprises, in combination with the draw-bar, movable friction plates or bars, between which are wedges, one of them being adapted to be moved with or by the draw-bar, while the other is held by a suitable stop, so that such motion of the draw-bar will first cause the wedges to expand and bear frictionally against the friction-plates and will then cause the latter to move in contact therewith with the desired frictional resistance.

Our invention also comprises a lever or other movable piece adapted to cause release

of the wedges from frictional contact, together with means for effecting the motion of said lever at or near the end of the working movement of the frictional devices.

Our invention is capable of modification in various ways by the skilled mechanic; but we show in the drawings what we believe to be the preferable construction.

In the drawings, 2 represents the draw-bar. 60 3 3 are the draft-irons, secured to the timbers and having fixed stops 4 4'.

5 5 are the friction-plates, which are adapted to move with the draw-bar buffing. These friction-plates are preferably connected together by top and bottom plates 6, which may be interlocked with the friction-plates, as shown at 6', and secured thereto by bolts or rivets. A head or follower 8 is connected to the friction-plates and is preferably interlocked therewith at 8'. The draw-bar 2 bears against the head 8 in buffing, and the follower 8 bears against the stops 4 in pulling. Between the friction-plates 5 5 are the wedges 9 and 10. The rear end of the wedge 10 is formed integrally with or bears against a head or follower 11, around which the yoke 12 of the draw-bar passes, and said follower has a bearing against the rear stops 4'. The wedge 9 is integral with or bears against a 80 head or follower 13, and a spring or springs 14 are interposed between the followers 8 and 13. The wedges are not coextensive, and the spaces b c at their ends permit their longitudinal motion. When the parts are in the 85 position shown in Fig. 1, if a buffing force is applied to the draw-bar it will move back the follower 8 and friction-plates 5 5 and by means of the spring 14 and follower 13 such motion will be transmitted to the wedge 9, 90 which will bear against the wedge 10, and the latter being held from rearward motion by the stops 4' the wedges will be expanded between the friction-plates 5 5 and will exert a frictional retarding action upon the latter, 95 which, together with the spring 14, imparts the desired yielding resistance to the draw-bar. If a pulling force is now applied to the draw-bar, the spring 14 will first react to bring the parts into the position shown in 100 Fig. 1, and the draw-bar will then act through the yoke 12 upon the rear follower 11, and

drawing against the wedge 10 will cause it to bind with the wedge 9, which is held by the spring 14 bearing against the follower 8 and stops 4. The continued forward motion of the draw-bar will move the wedges between the friction-plates 5 and against the spring 14 with the desired frictional action.

The above description explains our device in its simplest form, comprising merely the friction-plates, two wedges, and a spring, and we desire to claim the same broadly, whether the spring be placed on the forward end or rear end of the wedges. Our improvement, however, also comprises certain other features of importance. Thus in order to maintain frictional contact of the wedges in all conditions of wear and to render the device capable of automatically taking up slack, which is a matter of great importance, we not only incline the wedges longitudinally, as shown in plan view in Fig. 1, but we also incline or taper them transversely, as shown in Figs. 4 and 5, so that under the action of gravity they will always be maintained in contact with each other. For the purpose of preventing accidental upward creeping of the wedges, which would tend to release them from frictional contact, we incline somewhat the working faces 5' of the friction-plate 5 and correspondingly incline the outer face of the wedge 9, as shown in Fig. 2.

Our invention also provides means for the positive release of the friction-surfaces of the draft-rigging at or near the end of their motion, and for this purpose we provide a lever or-like moving part, which at the proper time is moved against one of the wedges and causes its release from the other. Simple forms of applying such device are shown in the drawings. In Figs. 1 to 9 a lever 15 is set in a socket 16 in the wedge 10 or follower 11 and bears against a pivot or fulcrum 17 therein, or the fulcrum may be formed on the lever instead of being formed in the socket 16. One end of the lever 15 has a bearing against the wedge 9, and the other end receives or bears against the rear end of a spindle 18, which preferably fits within the socket 19 on the lever and extends to within a short distance of the follower 8, the space between these two parts being a little less than the desired length of travel of the parts of the draft-rigging. The spindle passes longitudinally through holes 20 in the wedges, the hole in the wedge 10 being of larger diameter than the spindle, so as to permit the necessary downward gravity action of the latter for the purposes above explained. When the parts reach the limit of their rear motion in buffering, the follower 8 engages the spindle and moving it lengthwise will turn the lever 15 on its fulcrum 17 and will cause the latter to move the wedge 9 forward. This effects the immediate release of frictional contact between the wedges. In like manner in pulling when the

parts reach the limit of their forward motion the forward end of the spindle will engage the follower 8 and acting through the lever 15 will move the wedge 9 forward and release it.

In Fig. 10 we show a modified construction in which the spindle 18 is not employed. The lever 15' is pivoted at 17' to the wedge 10. One end bears against the wedge 9, and the other end is adapted to be engaged by one of the friction-plates 5 near the end of the motion of the parts.

Other means for effecting the positive release of the wedges through a movable piece or wedge will suggest themselves, and the skilled mechanic will be able to modify the other parts of our invention in many ways, since

What we claim is—

1. A frictional draft-rigging having an external friction member and wedges, one of said wedges being restrained by a stop and the other of said wedges being adapted to move with the draw-bar to effect the frictional engagement of the friction elements; substantially as described.

2. A frictional draft-rigging having an external friction member and wedges, one of the said wedges being adapted to be restrained by a stop, the other wedge being adapted to move with the draw-bar, and a spring bearing on one of said wedges; substantially as described.

3. In a frictional draft-rigging the combination with the movable friction members, wedges having a longitudinal face adapted to engage said movable friction members, a stop for one of the wedges, and a spring bearing against the other wedge; substantially as described.

4. In a frictional draft-rigging, the combination with external movable friction members, of wedges having lateral engagement therewith, a stop for one of the wedges, a spring bearing against the other wedge, and a head or follower connected to the friction-plates whereby the frictional engagement of the friction elements is effected; substantially as described.

5. In a frictional draft-rigging, the combination of movable friction members, wedges having a plain face upon one side, and a downwardly and transversely beveled face opposite thereto, a stop for one of the wedges, a spring bearing against the other wedge, a head or follower connected to the friction-plates, and a stop for said head or follower; substantially as described.

6. A frictional draft-gear comprising a friction-plate and another frictional member adjacent thereto, said friction-plate having its working face inclined to prevent vertical motion of the other friction member; substantially as described.

7. A frictional draft-rigging having wedge members in contact with each other, said

wedge members having transversely-inclined meeting faces to maintain their frictional contact; substantially as described.

8. A frictional draft-rigging having wedging friction members, and a movable piece adapted to be engaged at or near the limit of motion to cause their reverse motion and release; substantially as described.

9. A frictional draft-rigging having wedging friction members, a moving part carried with one of said members and adapted to be engaged at or near the limit of motion and to cause the reverse motion and release of the wedges; substantially as described.

10. A frictional draft-rigging having wedging friction members, a moving part carried with one of said members and adapted to be engaged at or near the limit of motion and to cause the reverse motion and release of the wedges; substantially as described.

11. A frictional draft-rigging having wedging friction members, and a movable piece adapted to be engaged by one of the moving parts of the draft-rigging at or near the limit of motion to cause their reverse motion and release; substantially as described.

12. A frictional draft-rigging having wedging friction members, and a lever adapted to be engaged at or near the limit of motion to cause their reverse motion and release; substantially as described.

13. A frictional draft-rigging having wedging members, a moving part carried with one of said members and adapted to be engaged at or near the limit of motion and to cause the reverse motion and release of the wedges, and a spindle extending loosely through the wedges, adapted to be engaged by a follower in said draft-rigging and to actuate said movable part, and a transversely-inclined surface adapted to maintain the frictional contact of the wedges by gravity; substantially as described.

14. A frictional draft-rigging having wedging friction members, and a lever carried with one of said members and bearing on the other, and means for actuating said lever at or near the limit of motion of the draft-rigging; substantially as described.

15. In a mechanism of the character indicated; a friction member, a spring-seat having frictional engagement with one side of

said friction member, a follower having frictional engagement with the opposite side thereof, and means whereby when the mechanism is subjected to strain said spring-seat and follower act upon each other to cause them to frictionally engage said friction member, substantially as described.

16. In a mechanism of the character indicated, a friction member, a spring-seat having frictional engagement with one side of said friction member, and a follower having frictional engagement with the opposite side thereof and having wedging engagement with said spring-seat to cause said seat and follower to frictionally engage said friction member when the mechanism is subjected to strain, substantially as described.

17. In a frictional draft-rigging, the combination with one or more friction members, of wedges having longitudinal faces for contact with said friction member or members, said wedges also having coacting inclined faces operating under draft and buffing movements of the draw-bar to cause a lateral expansion of the wedges against the friction member or members; substantially as described.

18. In a frictional draft-rigging, the combination of a friction member or members having friction-faces extending longitudinally of the rigging, of longitudinally-movable wedges having faces parallel with their lines of movement and contact with the friction member or members, said wedges also having coacting inclined faces, a spring bearing against one of the wedges, and means for restraining the lateral movement of the wedges; substantially as described.

19. In a frictional draft-rigging, the combination with a friction member or members, having friction-faces extending longitudinally of the rigging, of wedges contacting with the friction member or members, and having coacting inclined faces extending across the line of draft and arranged to expand the wedges upon longitudinal movement; substantially as described.

In testimony whereof we have hereunto set our hands.
